FUEL DISTRIBUTOR

Howard P. Anderson, Erie, Pa., assignor to The Standard Stoker Company, Incorporated, a corporation of Delaware

Application April 22, 1932, Serial No. 606,870

14 Claims. (Cl. 110—101)

This invention relates to fuel distributors for use with stokers which feed fuel such as coal into a furnace.

One of the important objects of the invention is the provision of a novel fuel distributor universally mounted with a stoker feed conduit to permit of angular adjustment of the axis of the fuel distributor.

Another object of this invention is the provision, in a fuel distributor having top and bottom fuel deflecting members, of means for variably adjusting each of said members about a horizontally extending, transverse axis, such means being controlled from without the furnace.

A further object of this invention is the provision, in a fuel distributor which extends forwardly from the delivery end of a stoker and which is in a flexible relation therewith whereby the axis of said distributor may be adjusted angularly, of fuel deflecting members which are adjustable independently of the fuel distributor as a whole.

Other and further objects of this invention reside in the construction of the distributor parts per se and their novel relations one with another as set forth in the following specification and illustrated in the accompanying drawings, in which

Figure 1 is a section through a furnace firing opening showing the distributor device of the invention in elevation with portions broken away;

Figure 2 is a plan view of the distributor device of the invention;

Figure 3 is a sectional view taken on the line 3—3 of Figure 2;

Figure 4 is an enlarged fragmentary view similar to a portion of Figure 3;

Figure 5 is a sectional view taken on the line 5—5 of Figure 1;

Figure 6 is a transverse section taken on the line 6—6 of Figure 5 looking in the direction of the arrows;

Figure 7 is an isometric view of the bottom deflector member shown in Figures 1 and 2; and

Figure 8 is an isometric view of the top deflector member shown in Figures 1 and 2.

The term "forward" as applied throughout the description and claims to parts of the device is used with reference to the direction that the fuel travels.

Referring now to these drawings, the furnace is shown at 10, having a front wall 11 and the firing opening 12 therein, through which projects the fuel distributor F of the stoking feed conduit S for scattering fuel over the firebed. Since this invention is chiefly concerned with the fuel dis-

tributing means, only so much of the stoker feed conduit S is shown as is necessary for a complete understanding of the invention.

The fuel distributor F comprises the body or tube member 14 having an arcuate top 15, the tubular rearward portion 16 and a forward portion including the depending parallel side walls 17 and 18. At its forward end, the fuel distributor is provided with the top deflecting member 19 and a bottom deflector 20, both of which extend into the furnace and serve to deflect the fuel evenly to all parts of the firebed as projected thereover by a blast of pressure fluid issuing from a suitable jet head such as at 64. In order that the maintenance cost of the stoker may be kept at a minimum, the fuel deflecting members 19 and 20 which are subjected to the intense heat of the furnace, are made separate from the fuel distributor F and are easily replaced.

It has been found in the installation of stokers to some types of furnaces, that due to variations in dimensions of the furnace and other factors such as draft conditions, perfect fuel distribution cannot always be attained except by alteration of the fuel distributor parts; this requires a repetition of work when these parts are renewed. To satisfactorily meet these peculiar conditions the present invention provides a fuel distributor adjustable bodily and in which its fuel deflecting parts are adjustable independently of one another and of the bodily adjustment of the distributor device.

In carrying out this invention, the bottom fuel deflector is arranged to be received by a frame 22 which is suspended at its rearward end from the pins such as 23, 24 which pass through the upright walls 25, 26 of the frame 22 and the depending parallel side walls 17, 18 respectively of the tubular support member 14. Extending downwardly and rearwardly of the frame 22 and formed therewith, is a flanged arm 27 which is apertured as at 28 to engageably receive a hand nut 29 threaded to receive a stud 30. The stud 30 is mounted upon the pivot pin 31 passing through the bracket 32 which is secured to the front wall 11 of the furnace 10.

The bottom deflector 20 comprises a flat portion 33 and the sidewardly curved channels 34, 35 surmounted by J-shaped abutments 36, 37 which converge into a common rib 38 extending to the foremost portion of said bottom deflector. The forward end portion 39 of the bottom deflector is provided with a relatively heavy section of metal in order to increase the heat absorbing capacity of this member to prolong its

life and also to maintain this deflector in its proper adjusted position.

Depending from the rearmost portion of the deflector bottom 20 is a hook 40 which is adapted 5 to pass through the aperture 41 in the frame 22 and engage the arcuate flange 42 thereof. The bottom wall 43 of the frame 22 is depressed as at 44 to allow the bottom deflector 20 to rest thereupon, the flat portion 33 of said deflector 10 forming a continuation of the horizontal wall 43 of said frame 22. It will be observed that the heavy forward end portion 39 of the deflector bottom 20 serves to retain this deflector in engagement with the frame or standard 22. In 15 effect, the bottom deflector 20 and the standard 22 form an adjustable floor portion of the distributor device.

The top fuel deflector 19 includes a relatively wide front portion 84, a rear portion 45 and the 20 ribs 46 which serve to rigidify the deflector 19 for preventing its sagging when subjected to the intense heat of the furnace 10. The rear portion 45 is provided with an ear 85 and the rearwardly and downwardly extending arm 47, which are 25 apertured as at 48 and 49 to receive the transversely extending pins 50 and 51 respectively. The pins 50 and 51 pass through the lugs 52 and 53 respectively, which are formed with the arcuate top 15 of the tube member 14 at the forward end thereof, and in this manner the top deflector 19 is hinged to the tube member 14.

Connected to the lowermost portion of the arm 47 by the pin 54 is a lever arm 55 which is slotted as at 56. A shouldered bolt 57 passes through 35 the slot 56 and is threaded into the tube member 14, forming a fulcrum for the lever arm 55. The lever arm is provided with a laterally extending flange 58 which is apertured as at 59 to engageably receive a hand nut 60 threaded to 40 receive a stud 61. The stud is mounted upon a pivot 62 passing through the bracket 63 (Figure 2) which is secured to the furnace 10 in a manner similar to that of the bracket 32.

Suitable means are provided for projecting the 45 fuel into the furnace and includes the jet head 64 secured to the underside of the tubular rearward portion 16 and having jet openings 65 disposed at a plane above the level of the bottom wall 43 of the frame 22. A bolt 66 passes through the 50 rearward portion of the jet head 64 and is received at its ends in the lugs 67, 68 formed with the underside of the tubular rearward portion 16, thereby securing said jet head against fore and aft movement. At its forward end, the jet head 55 64 is provided with the outwardly extending flanges 69, 69a which rest upon the downwardly and inwardly extending flanges 70 and 71 respectively, formed with the underside of the tubular portion 16. A supply line such as 72, 60 admits pressure fluid into the chamber 73 of the jet head 64, from where it is issued through the jet openings 65.

In some instances, it has been found that when 65 the stokers of this type are erected, perfect fuel distribution is not attained, even though the top and bottom deflectors are properly adjusted. This is due, in part, to variations in the dimensions of the furnace and also to uneven draft 70 conditions and the grade of fuel used. In order that it may be possible to readily and positively correct such faulty distribution of the fuel, the fuel distributor F is provided with a spherical flange 86, formed with the rearward portion of the tube member 14. The spherical flange 86 75 is received in a complementary seat 74, formed

with the delivery end of the stoker conduit S, and is held in any suitable angular relation therewith by a clamp 75 and the bolts 76 which pass through the flanges 77 and 78 of the delivery end 13 and the clamp 75, respectively. It will be observed that the adjacent faces of the flanges 77 and 78 are spaced apart sufficiently to allow the spherical flange 86 to be firmly clamped in the desired relation with the delivery end 13 of the feed conduit. Whenever it is desired to adjust 10 the axis of the fuel distributor F, the bolts 76 are loosened and the fuel distributor is pointed or aimed in the desired direction, after which the clamp 75 is caused to firmly engage the spherical flange 86 by tightening the bolts. 15

By forming a universal joint 79 between the feed conduit delivery end 13 and the fuel distributor F, it is possible for the fuel distributor to be virtually aimed in the desired direction 20 without affecting the distribution of fuel as determined by the adjustment of the top and bottom deflectors. It is understood that the jet head 64 is fixed with respect to the universally connected tube member 14, and hence, the jet head is movable with the tube member 14 and 25 is always in the same angular relation therewith.

In the operation of this distributor device, fuel which is discharged from the delivery conduit 13 of the stoker falls from the tubular rearward portion 16 of the fuel distributor F in front of 30 the jet head 64. The fuel is projected by a blast of pressure fluid issuing from the jet head 64 and is deflected to the desired portions of the furnace as determined by the position of the deflectors 19 and 20. The J-shaped abutments 36 and 37 of 35 the bottom deflector 20 intercept, in the instance shown, a major portion of the coal for lateral distribution. This is accomplished by merging the abutments 36 and 37 into a common rib 38 which extends to the rearmost portion of the 40 bottom deflector. However, if it is desired to intercept a greater or lesser amount of fuel for lateral distribution, the bottom deflector 20 may be raised or lowered by rotating the hand nut 29. It will be apparent that when the hand nut 45 29 is rotated to move it inwardly along the stud 30, the frame member 22, which is carried by the pins 23 and 24, will then be raised upwardly, and hence the abutments 36 and 37 of the bottom deflector will be elevated, serving to intercept more 50 fuel for lateral distribution. Conversely, when the hand nut 29 is rotated to move outwardly along the stud 30, the frame 22 and consequently the abutments 36 and 37 will be lowered, allowing more fuel to be projected forwardly into the 55 furnace. The top deflector 19 may be similarly raised or lowered by the proper manipulation of the hand nut 60.

From the foregoing it will be apparent that a novel fuel distributor has been provided in 60 which the deflectors at the forward end thereof are adjustable from without the furnace about a transversely extending, horizontal axis, which distributor is universally jointed to the delivery end of the stoker; thereby, producing a fuel distributor in which the distribution of the fuel may be effectively and readily controlled.

I claim:

1. In combination, a furnace having a firing opening in a wall thereof, a fuel delivery conduit, 70 a fuel distributor projecting into the furnace through said firing opening, means for connecting said fuel delivery conduit and said fuel distributor, said means arranged for permitting angular axial adjustment of said fuel distributor, 75

a jet head attached to said fuel distributor and movable therewith for projecting fuel into the furnace, said fuel distributor including detachable pivotally mounted fuel deflecting means 5 movable therewith, and means for effecting angular adjustment of said fuel deflecting means with respect to that portion of the fuel distributor to which the jet head is attached.

2. In combination, a furnace having a firing 10 opening in a wall thereof, a fuel delivery conduit, a fuel distributor projecting into the furnace through said firing opening, said fuel distributor including a tube member, means for connecting said fuel delivery conduit and said tube member 15 of the fuel distributor, said means arranged for permitting angular axial adjustment of said fuel distributor, a jet head attached to said tube member and movable therewith for projecting fuel from said tube member into the furnace, 20 pivotally mounted fuel deflecting means detachably connected to said tube member, and means for effecting angular adjustment of said fuel deflecting means with respect to said tube member.

3. In combination, a furnace having a firing 25 opening in a wall thereof, a stoker fuel distributor projecting into the furnace through said firing opening, said fuel distributor comprising a tube member, a top deflector detachably connected to said tube member at the forward end 30 thereof and arranged to be rotated for angular adjustment about a transversely extending axis, means for controlling the angular adjustment of said top deflector, a frame member attached to the lower portion of said tube member, said frame 35 member being provided with a fuel supporting surface and arranged to be rotated for angular adjustment about a transversely extending axis, means for controlling the angular adjustment of said frame member, a bottom deflector member 40 detachably secured to said frame member and means for projecting fuel across said bottom deflector member.

4. In combination, a furnace having a firing 45 opening in a wall thereof, a stoker fuel distributor projecting into the furnace through said firing opening, said fuel distributor comprising a tube member, a top deflector detachably connected to said tube member at the forward end 50 thereof and arranged to be rotated for angular adjustment about a transversely extending axis, means for controlling the angular adjustment of said top deflector, a frame member attached to the lower portion of said tube member, said frame 55 member being provided with a fuel supporting surface and arranged to be rotated for angular adjustment about a transversely extending axis, means for controlling the angular adjustment of said frame member, a bottom deflector member detachably secured to said frame member, and a jet head attached to said tube member and arranged to issue a blast of pressure fluid across said bottom deflector.

5. In combination, a furnace having a firing 60 opening in a wall thereof, a stoker fuel distributor projecting into the furnace through said opening, said fuel distributor comprising a tube member having an arcuate top, a rearward tubular portion and a pair of parallel sidewalls forward of said tubular portion, a top deflector member at the forward end of said tube member, a frame member at the lower portion of the tube member pivotally attached to said parallel sidewalls for angular adjustment about a transversely extending axis, said frame member being 65 provided with a fuel supporting surface, means

for controlling the angular adjustment of said frame member, and a bottom deflector member detachably secured to said frame member.

6. In combination, a furnace having a firing 70 opening in a wall thereof, a stoker fuel distributor projecting into the furnace through said opening, said fuel distributor comprising a tube member having an arcuate top, a rearward tubular portion and a pair of parallel sidewalls forward of said tubular portion, a top deflector member at the forward end of said tube member, a frame member pivotally attached to the lower part of said parallel sidewalls for angular adjustment about a transversely extending axis, said frame member being provided with a fuel sup- 75 porting surface, means for controlling the angular adjustment of said frame member, a bottom deflector member detachably secured to said frame member, and a jet head attached to said tube member and arranged to issue a blast of pressure fluid across said bottom deflector.

7. In combination, a furnace having a firing 80 opening in a wall thereof, a stoker fuel distributor projecting into the furnace through said opening, said fuel distributor comprising a tube member having an arcuate top, a rearward tubular portion and a pair of parallel sidewalls forward of said tubular portion, a top deflector member detachably connected to the forward end of said tube member and arranged to be rotated for angular movement about a transversely extending axis, means for controlling the angular adjustment of said top deflector, a frame member pivotally attached to the lower part of said sidewalls for angular movement about a transversely extending axis, said frame member being provided with a fuel supporting surface, means for controlling the angular adjustment of said frame member, and a bottom deflector member detachably secured to said frame member.

8. In combination, a furnace having a firing 85 opening in a wall thereof, a stoker fuel distributor projecting into the furnace through said opening, said fuel distributor comprising a tube member having an arcuate top, a rearward tubular portion and a pair of parallel sidewalls forward of said tubular portion, a top deflector member detachably connected to the forward end of said tube member and arranged to be rotated for angular movement about a transversely extending axis, means for controlling the angular adjustment of said top deflector, a frame member pivotally attached to the lower part of said sidewalls for angular movement about a transversely extending axis, said frame member being provided with a fuel supporting surface, means for controlling the angular adjustment of said frame member, a bottom deflector member detachably secured to said frame member, and a jet head attached to said tube member and arranged to issue a blast of pressure fluid across said bottom deflector.

9. In combination, a furnace having a firing 90 opening in a wall thereof, a stoker fuel delivery conduit, a fuel distributor projecting into the furnace through said opening, said fuel distributor comprising a tube member having an arcuate top, a rearward tubular portion and a pair of parallel sidewalls, means for connecting said fuel delivery conduit and said tube member, said means arranged for permitting angular axial adjustment of said tube member, a top deflector member detachably connected to the forward portion of said tube member and arranged to be rotated 95

for angular movement about a transversely extending axis, means for controlling the angular adjustment of said top deflector, a frame member pivotally attached to the lower part of said sidewalls for angular movement about a transversely extending axis, said frame member being provided with a fuel supporting surface, means for controlling the angular adjustment of said frame member, and a bottom deflector member detachably secured to said frame member.

10. In combination, a furnace having a firing opening in a wall thereof, a stoker fuel delivery conduit, a fuel distributor projecting into the furnace through said opening, said fuel distributor comprising a tube member having an arcuate top, a rearward tubular portion and a pair of parallel sidewalls, means for connecting said fuel delivery conduit and said tube member, said means arranged for permitting angular axial adjustment of said tube member, a top deflector detachably connected to the forward portion of said tube member and arranged to be rotated for angular movement about a transversely extending axis, means for controlling the angular adjustment of said top deflector, a frame member pivotally attached to the lower part of said sidewalls for angular movement about a transversely extending axis, said frame member being provided with a fuel supporting surface, means for controlling the angular adjustment of said frame member, a bottom deflector member detachably secured to said frame member, and a jet head attached to said tube member and arranged to issue a blast of pressure fluid across said bottom deflector.

11. In combination with a stoker fuel delivery conduit; a fuel distributor universally connected to said fuel delivery conduit, fuel deflecting means detachably connected to said fuel distributor, said fuel deflecting means arranged to be angularly adjusted about a horizontal, transverse axis, a jet head rigidly attached to said universally connected fuel distributor and means for effecting angular adjustment of said fuel deflecting means with respect to that portion of the fuel distributor to which the jet head is attached.

12. In combination with a stoker fuel delivery conduit; a fuel distributor comprising a tube member universally connected to said fuel delivery conduit, fuel deflecting means detachably connected to said tube member, said fuel deflecting means arranged to be angularly ad-

justed about a horizontal, transverse axis, a jet head rigidly attached to said tube member and means for effecting angular adjustment of said fuel deflecting means with respect to said tube member.

13. In combination, a furnace having a firing opening in a wall thereof, a stoker fuel delivery conduit, a fuel distributor projecting into the furnace through said opening, said fuel distributor comprising a tube member having a rearward tubular portion and a spherical flange formed with said tubular portion, a spherical seat in said fuel delivery conduit for receiving the spherical flange of said tubular portion, pivotally mounted fuel deflecting means detachably connected to said tube member, means for effecting angular adjustment of said fuel deflecting means, said means comprising an arm extending rearwardly from said fuel deflecting means, a threaded stud attached to the furnace wall and a threaded revolvable element engaging said arm and said threaded stud, a jet head attached to said tube member and arranged to issue a blast of pressure fluid for projecting fuel across said fuel deflecting means into the furnace, a clamp member firmly engaging said spherical flange for preventing movement of said spherical flange in said spherical seat, and means for relieving the engagement of said clamp member with said spherical flange whereby the tube member is rendered universally adjustable with respect to said stoker fuel delivery conduit.

14. In combination, a furnace having a firing opening in a wall thereof, a stoker fuel delivery conduit, a fuel distributor projecting into the furnace through said firing opening, means for connecting said fuel distributor and said fuel delivery conduit, said means being arranged for permitting angular adjustment of said fuel distributor, said distributor comprising a frame member provided with a fuel receiving surface, said frame member being pivotally mounted in the lower portion of said distributor, means for adjusting and securing said frame member in any one of a number of positions, fuel deflecting means detachably secured to said frame member, and a jet head attached to said fuel distributor at the rear of said frame member and arranged to issue a blast of pressure fluid across the fuel receiving surface of said frame member and across said fuel deflecting means.

HOWARD P. ANDERSON.
